UNITED STATES PATENT OFFICE.

SVERRE HILLAND, OF NEW YORK, N. Y.

RIVET CATCHER.

Application filed May 14, 1927. Serial No. 191,519.

Heretofore when rivets have been heated to redness or hotter for the purposes of being placed in a hole in the frame-work of a building which is being erected, it has been 5 common to throw the rivet to a man who catches it in a bucket and thereafter uses a pair of tongs to grab the hot rivet and place it in a hole so that it can be riveted in the conventional manner. He has to place 10 the bucket on the floor or beam where he stands while he helps get the rivet in place and secure the same. A bucket such as is ordinarily used is not advantageous because it is clumsy to handle, a rivet caught in it 15 may bound out, the tongs used for capturing the rivet in the bucket are not directed to the rivet by the walls of the pail and when the pail is put on a beam or floor it is apt to roll and fall.

20 The object of my invention is to provide a rivet catching device which is made of sheet metal and given a shape somewhat similar to that of a truncated cone, flattened at the apex, as indicated in the accompanying drawings, and this is provided with a 25 reinforce, so that it will be sufficiently strong, and a handle by which it may be easily manipulated. This catcher, when held in the hand of a mechanic, can be put in any desired 30 position so as to easily catch a rivet when thrown. Its converging walls prevent the rivet from bounding out and guide the tongs of the person capturing the rivet just where they belong and when this catcher is 35 discarded and placed on the floor or beam it will not roll. Its pointed end may be placed against the wind to keep wind from blowing it. When there is no wind, it may be stood on its open end and in any event it 40 may easily be placed so that the handle can be quickly reached so that a more reliable and easier manipulated rivet catcher is formed by my invention, one embodiment of which is hereinafter more particularly set 45 forth.

For a more detailed description of my invention, reference is to be had to the accompanying drawings, forming a part hereof, in which

50 Figure 1 is a side elevation of my improved rivet catcher.

Figure 2 is a front elevation of the same.

Figure 3 is a plan view.

55 Figure 4 is a sectional view, taken on the line 4—4 of Figure 3, looking in the direction of the arrows.

Figure 5 is a diagrammatic sectional view which shows the bottom joined.

Throughout the various views of the drawings, similar reference characters designate 60 similar parts.

My improved rivet catcher 1 has a sheet metal body 2, a reinforce 3, a handle 4 and screws or rivets 5 which secure the handle to the body.

65 The body 2 has a bead 6 at its open end and the body is shaped, as above stated, so as to resemble a cone, but be different therefrom because its bottom is an elongated surface and not a point, as indicated. This 70 body, near the handle, has a seam 7 by which the ends of the blank are united.

75 The reinforce 3 has a corresponding shape with its seam 8 on the side opposite from the seam 7 and this reinforce extends up to the top of the body 2 under the handle, but not elsewhere, the general shape being substantially as indicated. The bottom of the reinforce and the body are folded in together as shown in Figure 5 where one end 9 of the 80 body 2 stops abruptly. The corresponding end of the reinforce 3 on the same side extends laterally at 10 and then downwardly at 11 and backwardly at 12 to form a hook which is engaged by corresponding hooks 13 85 which come from the lower ends of the parts of the body 2 and reinforce 3 which are opposite to the parts shown at the left of Figure 5. The parts 10, 11, 12 and 13 are flattened together and so interlock and firmly 90 held when the rivet catcher is assembled.

95 The handle is given a concave convex curvature in cross section from rivet 5 to rivet 5, as nearly as may be, so that the handle can be held with convenience by the operator and he can place the catcher with great ease and exactness anywhere within his reach. The concave curvature is preferably outwardly because it is easier to grasp the handle when made this way.

100 In view of the foregoing, it is obvious that the rivet catcher here described has the advantages set forth above.

While I have shown and described one embodiment of my invention, it is also obvious that it is not restricted thereto, but that it is broad enough to cover all structures that come within the scope of the annexed claims.

105 Having thus described my invention, what I claim is:

110 1. A rivet catcher with converging sides, a

bottom, the bottom and converging sides being so proportioned with respect to each other that a rivet when thrown into the open end of the device will be directed to and held in a position nearly parallel to the bottom and nearly parallel to one converging side.

2. A rivet catcher with a handle secured to one of two converging sides, a bottom, the bottom and converging sides being so proportioned with respect to each other that a rivet when thrown into the open end of the device, will be directed to and held in a position nearly parallel to the bottom and nearly parallel to one converging side.

3. A rivet catcher with converging sides, one of which is reinforced, a bottom, the bottom and converging sides being so pro-

portioned in respect to each other that a rivet when thrown into the open end of the device will be directed to and held in a position nearly parallel to the bottom and nearly parallel to one converging side.

4. A rivet catcher with a handle attached to one of two converging sides, a reinforcing attached to the side with the handle, a bottom, the bottom and converging sides being so proportioned with respect to each other that a rivet when thrown into the open end of the device will be directed to and held in a position nearly parallel to the bottom and nearly parallel to one converging side.

In testimony whereof, I have hereunto set my hand this 12th day of May, 1927.

SVERRE HILLAND.
